ARTHUR GINGRAS, OF PAWTUCKET, RHODE ISLAND, ASSIGNOR OF ONE-HALF TO
ROBERT C. REETZ, OF PAWTUCKET, RHODE ISLAND.

LOOM SHUTTLE.

Application filed January 4, 1928. Serial No. 244,489.

My invention relates to a loom shuttle, and more particularly to a loom shuttle arranged to carry a plurality of quills for the purpose of feeding a weft of a plurality of threads, as the weaving progresses.

Considerable annoyance has hitherto been caused by the breaking of one of the threads while the weaving progressed to a greater or lesser extent with the other thread, thereby producing a defect in the fabric. This has happened because of the difficulty on the part of the operator to observe at a glance whether one or both of the threads were intact.

15 The primary object of my present invention is to provide a simple and efficient means for severing or cutting a companion thread when for any cause one of the threads of the group being fed is broken, thus calling prompt attention to the fact of the breakage and preventing the weaving of one of the threads independently of its companion thread.

A more specific object is to provide automatic thread severing means of the above kind which is extremely simple and durable in construction as well as efficient in operation.

25 A practical embodiment of my invention is illustrated in the accompanying drawing, in which:

Figure 1 is a top plan view of a two-quill shuttle, showing the parts in the position which they assume when the shuttle is in 35 operation;

Figure 2 is a side elevational view of the shuttle shown in Figure 1;

Figure 3 is an enlarged fragmentary longitudinal section taken upon line 3—3 of 40 Figure 1; and

Figure 4 is a view similar to Figure 3 with the parts shifted after the breakage of a companion thread has permitted severing of the other thread.

45 Referring more in detail to the drawing, 5 designates the shuttle, the same having the usual quill cavity 6. In this cavity are arranged two quills 7 and 7^a in the usual manner, the threads from said quills being 50 adapted to be fed out of the shuttle through the eyelets 8 and 8^a, arranged in one of the side walls thereof. Within the space between the free ends of the quills 7 and 7^a, and arranged inwardly of the eyelets 8 and 55 8^a is arranged a suitable thread-tension de-

vice 9 which cooperates with the threads of both of the quills.

The eyelets 8 and 8^a are preferably although not necessarily, disposed in spaced vertically aligned relation, and pivoted for vertical swinging movement upon the inner face of the adjacent side wall of the shuttle as at 10 and 10^a, are thread severing or cutting knives 11 and 11^a which are mounted to freely lower by gravity. The pivots 10 and 10^a are respectively located at opposite sides of the vertical plane intersecting the eyelets 8 and 8^a, and the knives 11 and 11^a project toward each other from these pivots with their adjacent free ends arranged to swing across the openings of the eyelets 8 and 8^a at the inner ends of the latter. Rigidly fastened at one end, by soldering or the like as at 12, to the knife 11 inwardly of its pivot 10 is an arm 13 which has its lower end directed toward the knife 11^a and formed with a terminal eye 14 adapted to register with the eyelet 8^a when the knife 11 is disposed with its free inner end directly above the eyelet 8 as shown in Figure 3. 70 The eye 14 forms a thread guide through which the thread of the quill 7^a is passed, and it will thus be seen that when this thread is placed under tension and the shuttle is in operation, the eye 14 will be maintained in registry with the eyelet 8^a so as to hold the knife 11 elevated with its free inner end disposed above the eyelet 8^a. In a like manner, an arm 13^a is rigidly secured by soldering or the like as at 12^a to the knife 11^a outwardly of its pivot 10^a, said arm 13^a extending upwardly and toward the free inner end of knife 11 so as to register with the eyelet 8 when the knife 11^a is positioned with its free inner end disposed directly 75 above the eyelet 8^a, as is also clearly shown in Figure 3. The free upper end of the arm 13^a is provided with a terminal eye 14^a through which the thread from the quill 7 is adapted to be passed, and it will thus be 80 seen that when the thread of the quill 7 is under tension and the shuttle is in operation, the eye 14^a will be maintained in registry with the eyelet 8 and the knife 11^a will be held positioned with its free inner 85 end above the eyelet 8^a. In order to insure effective engagement of the knives 11 and 11^a with and cutting of the threads, the free inner end portions of said knives are provided in their lower edges with V-shaped 90

notches 15, the walls of which are sharpened to form cutting edges. Undue upward swinging movement of the knives 11 and 11^a may be prevented by any suitable means 5 such as outwardly projecting lugs or fingers 16 provided on the pivoted ends of the knives, and stop pins 17 projecting inwardly from the adjacent side wall of the shuttle below and in the path of the lugs or 10 fingers 16.

The normal positions of the knives and arms are indicated in full lines in Figure 3, and they lower by gravity from their normal positions as shown in Figure 4, only when 15 the eyes 14 and 14^a are permitted to lower out of registry with the eyelets 8 and 8^a. This happens only when the eyes are freed, from their positions in registry with the eyelets 8 and 8^a, by the breaking of the 20 threads.

When, for any cause, one of the threads breaks, as, for example, the thread from the quill 7, it will immediately relieve the eye 14 and permit the knife 11 to lower by gravity 25 and sever the thread from the quill 7^a passing through the eye 14^a. In the same manner, if the thread from the quill 7^a should break it will relieve the eye 14^a and thereby permit the knife 11^a to lower by 30 gravity and sever the thread from the quill 7 which passes through the eye 14.

The above arrangement thus provides for promptly severing the companion thread when for any reason one of the threads 35 breaks, thus calling the operator's attention to the defect and enabling him to correct it before serious damage is done.

I am aware that the invention is susceptible of many modifications and changes 40 within the scope of the appended claims, such as the use of actuating springs for causing the cutting movement of the knives, the use of various forms of knives, and different arrangements and mountings of the 45 knives. Such minor changes are accordingly within the spirit and scope of the invention, although I have herein described what is at present deemed to be the preferred embodiment thereof.

50 What I claim as new is:—

1. A shuttle provided with means for supplying separate threads, and separate means under the control of each of the threads and actuated for cutting a companion thread 55 when one of the threads breaks.

2. A shuttle provided with means for supplying separate threads, and knives movable across the paths of said threads, said knives being under control of the threads and actuated to sever a companion thread when one 60 of the threads breaks.

3. A shuttle provided with means for supplying separate threads and having separate eyelets in a side wall thereof through which 65 the respective threads are adapted to be fed,

and knives pivoted on said side wall to respectively swing across said eyelets, said knives being under control of the threads and actuated to sever a companion thread when one of the threads breaks.

70

4. A shuttle provided with independent quills for supplying separate threads, knives movable across the paths of the threads and thread guides arranged for placing the said movable knives under the control of the 75 threads from the quills, the knife corresponding to each quill being under the control of the thread from the companion quill whereby the breaking of the thread from one of the quills will release the knife corresponding to the other quill to sever its thread.

80

5. A shuttle provided with independent quills, means for conducting the threads from the quills to separate outlets from the 85 shuttle, knives mounted between the inner ends of the quills to freely lower by gravity across the paths of said threads, said knives being provided with eyes adapted to be located in position to receive the threads therethrough as they extend from the quills to the exterior of the shuttle, the eye of the knife corresponding to each of the quills being adapted to be positioned to receive the thread leading from the opposite quill 90 whereby the releasing of one of the eyes by the breaking of a thread from one of the quills will permit the knife of the released eye to lower and sever the thread from the other quill.

100

6. A shuttle provided with independent quills, means for conducting the threads from the quills to separate outlets from the shuttle, knives mounted between the inner ends of the quills to freely lower by gravity 105 across the paths of said threads, said knives being provided with eyes adapted to be located in position to receive the threads therethrough as they extend from the quills to the exterior of the shuttle, the eye of the knife corresponding to each of the quills being adapted to be positioned to receive the thread leading from the opposite quill 110 whereby the releasing of one of the eyes by the breaking of a thread from one of the quills will permit the knife of the released eye to lower and sever the thread from the other quill. 115

120

7. A shuttle provided with independent quills, means for conducting the threads from the quills to separate outlets from the shuttle, knives mounted between the inner ends of the quills to freely lower by gravity 125 across the paths of said threads, said knives being provided with eyes adapted to be located in position to receive the threads therethrough as they extend from the quills to 130

the exterior of the shuttle, the eye of the knife corresponding to each of the quills being adapted to be positioned to receive the thread leading from the opposite quill 5 whereby the releasing of one of the eyes by the breaking of a thread from one of the quills will permit the knife of the released eye to lower and sever the thread from the

other quill, said outlets embodying vertically spaced eyelets on a side wall of the 10 shuttle, said knives being pivoted in the inner side of said side walls, and means to limit the upward movement of the knives.

In testimony whereof I affix my signature.

ARTHUR GINGRAS.
